UNITED STATES PATENT OFFICE.

ANDREW EPPLER, OF LYNN, AND WALTER V. NEAL, OF BOSTON, MASSACHUSETTS,
ASSIGNORS TO UNITED SHOE MACHINERY CORPORATION, OF PATERSON, NEW
JERSEY, A CORPORATION OF NEW JERSEY.

SHOE-TURNING MACHINE.

1,307,811.

Specification of Letters Patent. Patented June 24, 1919.

Application filed April 13, 1918. Serial No. 228,366.

To all whom it may concern:

Be it known that we, ANDREW EPPLER and WALTER V. NEAL, citizens of the United States, residing at Lynn, in the county of 5 Essex, Commonwealth of Massachusetts, and Boston, county of Suffolk, Commonwealth of Massachusetts, respectively, have invented certain new and useful Improvements in Shoe-Turning Machines; and we do hereby 10 declare the following to be a full, clear, and exact description of the invention, such as will enable others skilled in the art to which it appertains to make and use the same.

The present invention relates to shoe turning machines and more particularly to machines of this character employed for turning the forepart of a shoe.

Inasmuch as turn shoes vary materially both in size, shape and the character and 20 strength of the upper, it is desirable that the turning operation shall be controlled manually in order to avoid tearing of the upper or otherwise damaging the shoe. The hand turning operations, whether practised with 25 or without a machine, become exceedingly burdensome, however, if any considerable number of shoes have to be turned especially when turning the heavier grades.

It is the object of the present invention, 30 therefore, to provide a shoe turning machine having a simple and compact construction and which permits the turning of the shoe by the operator to be performed with the minimum of effort and liability of damage 35 to the shoe.

With this object in view the several features of the invention consist in certain novel features of construction, combinations and arrangements of parts hereinafter described 40 and claimed, the advantages of which will be obvious to those skilled in the art from the following description.

In the accompanying drawings illustrating the preferred form of the invention, 45 Figure 1 represents a side elevation of a machine embodying the several features of the invention; Fig. 2 is a front elevation of the machine shown in Fig. 1; and Fig. 3 is a detail showing the construction of the 50 forepart spreader.

In shoe turning machines it is customary to bend the sole over a turning post and to then perform the turning operation by a relative movement of the shoe and turning

post, the turning of the upper progressing 55 from the ball toward the toe of the shoe. The present machine is provided with a turning post over which the shoe sole is bent, and coöperating members located upon opposite sides of the turning post to engage, 60 respectively, with the heel and toe portions of the shoe. The relative movement of the shoe and turning post is accomplished by drawing the heel portion of the shoe downwardly away from the end of the turning 65 post while the toe portion of the shoe is held stationary. In order to permit this receding movement of the heel clamp the turning post is moved in the same direction at a lesser speed, which is approximately one-half the 70 speed of the heel end of the shoe, thus maintaining the bend in the sole without straining the sole unduly. The downward or receding movement of the heel clamp is imparted by a manually operated treadle so 75 designed that it may be conveniently actuated by the foot of the operator. This construction enables the turning of the forepart to be accomplished with a minimum of effort but at the same time permits the operator to 80 observe and feel the turning of the upper which may be immediately stopped if too great a strain is placed thereon.

In the illustrated embodiment of the invention the frame is provided with an upright arm 11 which carries a yoke 12 at the upper end. This yoke is provided with a shank 13 secured in the arm 11 by a clamp screw 14. A forepart spreading member is supported by the yoke in a position to conveniently enter the forepart of a shoe and comprises a pair of oppositely disposed curved fingers 15 shaped to conform approximately to the interior of the forepart and adjustably secured at their upper ends 90 to a swinging head indicated at 17. The head, as shown clearly in Fig. 3 of the drawings, comprises a pair of levers 16 which are pivoted upon a hub 65 at 66. The outer ends of the two levers are normally 100 spread apart by a compression spring 67 interposed between the levers and adjusted by a member 68 threaded in one of the levers 16, as shown. The opposite ends of the levers are conveniently spread apart to 105 decrease the effective width of the forepart spreader by an adjusting member 70 threaded in one of the levers and engaging with

the coöperating lever. An additional adjustment of the spreading fingers independently of one another is secured by providing a transverse slot 18 in each finger which receives a clamping screw 19 threaded in the end of the respective lever. This construction permits the simultaneous in and out adjustment of both fingers or an independent adjustment of the two fingers as desired.

10 The forepart spreader has provision for a bodily vertical adjustment and to this end the hub 65 is adjustably secured to a stud 20 mounted in the rear end of a U-shaped member 21, the clamping screw 22 threaded 15 in the hub serving to retain the spreader in any adjusted position. The opposite arms of the U-shaped member 21 are provided with trunnions 24 pivoted in the opposite arms of the yoke 12. This permits the forepart 20 spreading member to swing outwardly from the position shown in full lines to that shown in dotted lines in Fig. 1, a stop member 23 serving to limit the outward movement of the spreader, as shown. This stop member 25 is secured to the under side of one arm of the yoke 12 and is adapted to engage with the corresponding arm of the U-shaped member 21 when the latter swings down under the action of gravity. This tendency on the 30 part of the forepart spreader to move outwardly will be readily apparent when it is observed that the head 17 is located at one side of the trunnions 24. The spreader in its inclined position is conveniently located 35 to receive a shoe upper. After the spreader has been inserted within the shoe upper it is swung into a vertical position so that the shoe sole may be bent over a vertical turning post 25. When the forepart spreader is in 40 this position the toe of the shoe is engaged by a stationary member 27 adjustably secured at its lower end in a boss 28 forming a part of the machine frame. The heel end of the shoe which has been previously turned 45 envelopes one member 29 of a heel clamp which projects laterally and is provided with an under face 30 adapted to engage with the back of the counter. This member 29 of the heel clamp is formed upon the upper end of 50 a vertical slide 32 movable in ways formed in the machine frame and having a co-operating clamping member 34 pivoted thereon at 35. The coöperating members of the heel clamp are connected with the treadle 55 in such a manner that upon an initial actuation of the treadle the two clamps are moved together to engage the heel seat of the shoe between them and upon a continued actuation of the treadle the clamps are moved 60 away from the end of the turning post, carrying the heel end of the shoe with them. To this end the clamping member 34 is formed as one arm of a bell crank lever pivoted at 35 and having its second arm 37 connected to a swinging arm 39 through a link

40. The arm 39 is pivoted upon the frame of the machine at 42 and is connected to a treadle 43 by a link 44. With this construction when the treadle is initially depressed the bell crank carrying the clamping member 34 is rocked about the pivot 35 to cause the two clamping members 29 and 34 to engage the heel seat of the shoe between them. Thereafter the continued movement of the treadle depresses the slide 32 causing a bodily downward movement of the two clamps together with the heel end of the shoe. At the completion of the turning operation the clamp is returned to its initial position by a spring 45 connecting the outer end of the 70 treadle with a boss 46 projecting from the machine frame.

The turning post is moved in the same direction as the heel clamp as the turning operation progresses and to this end is conveniently actuated from the slide 32 carrying the heel clamps. As will be obvious from an inspection of Fig. 1 the turning post 25 is formed upon a vertical slide 50 received in the machine frame and adapted to move 85 parallel to the direction of movement of the slide 32. The slide 32 carrying the heel clamps is provided with a rack 52 which meshes with a small pinion 53 journaled in stationary bearings in the machine frame. 90 This pinion meshes with a larger intermediate gear 55 which carries a smaller driving gear 56 upon the same shaft. The gear 56 meshes with a rack 58 formed upon the turning post slide 50 and serves to move the 100 turning post slide in the same direction as the slide 32 but at a slower rate of speed. In the drawings the plate covering the slides and driving gears has been removed to enable the construction to be more readily observed.

It will be clearly evident that with this machine the operation of turning the forepart of a shoe upper is greatly facilitated without detracting from the intimate control 110 of the turning operation by the operator. It will be further obvious that by making the proper adjustments of the forepart spreader and the coöperating toe member the toe of the shoe may be firmly held in a stationary position during the movements of the turning post and heel clamp relative thereto. As will be observed from an inspection of Fig. 2 of the drawings the turning post is comparatively narrow in width 115 and is adapted to break the sole both longitudinally and transversely, a small roll 60 journaled in the top of the post tending to eliminate the friction of the sole in passing over the post during the turning operation.

While it is preferred to employ the specific construction and arrangement of parts shown and described, it will be understood that this construction and arrangement is not essential except so far as specified in the 125 130

claims, and may be changed or modified without departing from the broader features of the invention.

The invention having been described, what is claimed is:

1. A shoe turning machine having, in combination, a turning post, means for holding the forepart of a shoe at one side of the post, a pair of heel clamping members at 10 the opposite side of the post, a treadle, and connections for first closing the clamping members upon the shoe and for thereafter moving both clamping members and the turning post to turn the shoe over the post 15 during a continued movement of the treadle in one direction.

2. A shoe turning machine having, in combination, a turning post, means for holding the toe of a shoe stationary at one side 20 of the post, means for engaging with the heel of the shoe upon the opposite side of the post, and manually actuated mechanism for moving the heel engaging member and turning post in the same direction and at different 25 speeds to turn the shoe over the post.

3. A shoe turning machine having, in combination, a turning post, means for holding the toe end of a shoe stationary at one side of the post, means for drawing the heel 30 end of the shoe downwardly, and connected mechanism for simultaneously moving the turning post in the same direction at a slower rate of speed.

4. A shoe turning machine having, in combination, a forepart spreader member, means coöperating therewith to retain a shoe in position upon the spreader, a turning post about which the sole of the shoe is bent, and means for drawing the heel end of the shoe 40 away from the turning post to turn the shoe about the post while the toe end of the shoe is held stationary.

5. A shoe turning machine having, in combination, a forepart spreader, means for 45 normally retaining the spreader in an inclined position for the convenient reception of a shoe, a vertical turning post, a heel clamp, and manually actuated means for drawing the heel clamp away from the end 50 of the turning post to turn the shoe over the post.

6. A shoe turning machine having, in combination, a turning post, a vertically movable slide carrying the turning post, a 55 stationary toe engaging member located at one side of the turning post, a heel engaging member located upon the opposite side of the turning post, a vertically movable slide

carrying the heel member and manually actuated mechanism for moving the two slides 60 in the same direction.

7. A shoe turning machine having, in combination, a turning post, means for holding the toe end of a shoe at one side of the post, a pair of heel clamping members located upon the opposite side of the post, a manually actuated treadle member, and connections between the treadle member and heel clamping members for first closing the clamping members upon the shoe and for 70 thereafter moving both clamping members away from the end of the turning post during a continued movement of the treadle member in the same direction.

8. A shoe turning machine having, in combination, a pair of slides moving in parallel paths, a turning post mounted upon one slide, a heel engaging member mounted upon the second slide at one side of the turning post, a stationary toe engaging member located at the opposite side of the turning post, mechanism for actuating the heel clamp slide, and connections between the two slides for simultaneously actuating the turning post in the same direction and at a 85 slower speed.

9. A shoe turning machine comprising a pair of fingers adapted to be received within the forepart of a shoe, a pivoted lever supporting each finger, and means for simultaneously rocking the two levers about the pivotal connections to vary the effective width of the forepart spreader.

10. A shoe turning machine comprising a head, a plurality of spreader fingers supported upon the head, and a swinging frame fulcrumed above and at one side of the head so that the head normally maintains the spreader fingers in an inclined position for the convenient reception of a shoe.

11. A shoe turning machine comprising a pair of spreader fingers, means for simultaneously adjusting the fingers toward and from one another, and separate means for independently adjusting the fingers toward 105 and from one another.

12. A shoe turning machine comprising a pair of fingers, means for simultaneously adjusting the fingers toward and from one another, separate means for independently adjusting the fingers toward and from one another, and means for securing a bodily lengthwise adjustment of the fingers.
